RECORD TRANSFER DEVICE FOR AUTOMATIC PHONOGRAFS

Filed April 10, 1934

Fig. 1.

UNITED STATES PATENT OFFICE

2,098,601

RECORD TRANSFER DEVICE FOR AUTO-
MATIC PHONOGRAHSJohn H. Teaf, Camden, N. J., assignor to Radio
Corporation of America, a corporation of Dela-
ware

Application April 10, 1934, Serial No. 719,831

22 Claims. (Cl. 274—10)

This invention relates to automatic phonographs of the type wherein a plurality of records stacked on a turntable are successively played and then removed to a record receptacle, and more particularly to the means for holding the records properly on and removing the played records from the stack.

Specifically, my invention constitutes an improvement upon the record ejector arm disclosed and claimed in the co-pending application of Benjamin R. Carson, Serial No. 700,492, filed on December 1, 1933, and assigned to the Radio Corporation of America. In said application, there is shown an automatic phonograph of the type indicated above wherein a plurality of disc records are threaded on a retractable center pin and are maintained, during playing of the topmost record of the stack, in pressing engagement with the turntable by a record ejector arm pivotally mounted to one side of the turntable for both horizontal and vertical movement. The free end of the arm is provided with a universally mounted friction disc by means of which most of the weight of the arm is concentrated on the records of the stack and with a finger which extends through the center opening of the topmost record of the stack and depresses the center pin the thickness of that record when said friction disc rests thereupon. At the completion of playing of a record, suitable mechanism imparts a horizontal movement to the ejector arm to cause the arm to move the played record toward the record receptacle, the arm being raised from the record and returned into engagement with the next succeeding topmost record when the previously played record has been moved substantially clear of the stack.

In order to apply sufficient pressure to the stack during reproduction, the ejector arm of the Carson machine is made comparatively heavy. However, this causes the arm to drop down onto the record stack with great force and not only endangers the life of the records, but also occasionally causes the needle, already in engagement with the topmost record of the stack, to jump several grooves, whereby the first portion of the selection is lost. Moreover, the Carson machine lacks means for insuring that the ejector arm will remain in elevated position when raised to its highest vertical position to permit loading of records on the turntable, this feature being desirable to prevent the ejector arm from accidentally falling upon the records and injuring them while they are being loaded.

The primary object of my invention is to provide an improved record ejector arm for a phonograph of the type set forth which will at all times be effective to apply sufficient pressure to the stack to insure proper friction or gripping action between the several records thereof, but which will, nevertheless, be capable of coming to rest gently upon the topmost record of the stack.

A further object of my invention is to provide an improved ejector arm the effective weight of which will vary with its state of operation.

Still a further object of my invention is to provide an improved ejector arm which will be capable of applying relatively great pressure to the stack during playing of a record.

Another object of my invention is to provide an improved ejector arm which will be ineffective to apply great pressure to the stack at the time that it comes into engagement with the topmost record thereof.

Still another object of my invention is to provide an improved ejector arm which will positively remain in elevated position when raised thereto, as during loading of records.

It is a further object of my invention to provide an improved ejector arm which is simple in construction, inexpensive of manufacture, and very efficient and quiet in operation.

In accordance with my invention, I place a movable mass within the hollow ejector arm and arrange the mass in such a manner that it is free to assume a position adjacent the horizontal pivot of the ejector arm while the arm is being returned to record engaging position on the stack, the mass being ineffective, in this position, to cause the arm to engage the topmost record with any great force. However, after the friction disc of the arm has engaged the topmost record of the stack, the mass, preferably in the form of a roller, is free to move to the free end of the arm, and, in this position, its weight causes a relatively great force to be applied to the stack, so that sufficient friction is maintained between the several records of the stack to prevent slipping therebetween. When the ejector arm is raised to its elevated position, the mass moves to a position where its center of gravity is somewhat beyond the horizontal pivotal axis of the arm and produces a sufficient moment to counterbalance the arm and retain it positively in elevated position.

In the appended claims, the novel features that I consider characteristic of my invention are set forth with particularity. The invention itself,

however, both as to its organization and method of operation, together with additional objects and advantages thereof, will best be understood from the following description of a specific embodiment when read in connection with the accompanying drawing, in which

Figure 1 is a sectional view showing my improved ejector arm applied to a stack of turntable supported records;

10 Figure 2 is a sectional view on the line II—II of Figure 1;

15 Figure 3 is a fragmentary view, partly in section, showing, in full lines, the position assumed by the ejector arm immediately after having re- moved the previously played record, and showing, in dot-and-dash lines, the position to which the arm is moved when it is desired to load records on the turntable;

20 Figure 4 is a fragmentary plan view showing the position of the ejector arm corresponding to that shown in Figure 1; and

25 Figure 5 is a fragmentary plan view showing the position of the arm corresponding to the solid line position of Figure 3.

30 Referring to the drawing more in detail, a motor board 1 supports a suitable motor (not shown) for driving a hollow spindle 2 extending through an opening 3 in the motor board, the spindle 2 carrying a turntable 4 on which a plurality of records R are supported in stacked relation. The records R are threaded on a center pin 5 retractable within the hollow spindle 2, the center pin 5 being constantly urged upwardly by a coil spring 6 within the spindle 2 and being limited 35 in its vertical travel, both upwardly and downwardly, by reason of a fixed pin 7 extending through the elongated slot 8 thereof.

35 Staked or otherwise suitably secured to the motor board 1 at one side of the turntable 4 is a bushing 10 in which is pivoted a pin 11 staked to a yoke 12, the bushing 10 having a reduced portion 10a extending a substantial distance below the motor board. The yoke 12 supports a horizontal shaft or pin 13 which pivotally supports a second yoke 14 for swinging movement in a vertical direction, the yoke 14 being provided with a pair of vertically-spaced lateral extensions 15 and 16. The lower extension 16 is provided with a pin 17 which extends down through an arcuate opening 18 in the motor board 1 into the path of movement of a cam plate 19 which is provided with a hub 20 rotatable on the bushing extension 10a, while the upper extension 15 is provided with an adjustable screw 21 adapted to cooperate with a record ejector arm 22 for lifting it. The ejector arm 22 is also mounted on the pin 13 and, when engaged by the screw 21 during upward travel of the yoke 14, is forced upwardly to partake of 60 vertical movement in response thereto.

65 The ejector arm 22 consists of a bottom plate or base member 23 preferably provided with a pair of spaced, upstanding guides 24 and a pair of downwardly extending ears or lugs 25 by means of which the arm 22 is mounted on the pin 13, a cover 23a being supported on the base 23 and providing, with the base 23 and the guides 24, a hollow space within which is confined a freely movable mass M, preferably a roller, of substantial weight. The free end of the plate 23 is apertured to receive a hollow, internally threaded bolt 26 secured to the plate 23 by a nut 27, the nut 27 also holding in place on the bolt 26 a bracket member 28 to which is secured a resilient shock-absorbing bumper 29 for a purpose here-

5 inafter more fully described. The opposite end of the arm 22 is also provided with a shock absorbing bumper 30 also to be referred to more in detail hereinafter, the bumpers 29 and 30 being, preferably, of sponge rubber.

10 Threaded into the bolt 26 is a center pin depressing finger 31 having an enlarged head 32, the finger 31 being locked to the bolt 26 by a nut 33 in desired relation to the rounded head of the bolt 26. The head 32 is spaced from the head 10 of the bolt 26 a distance sufficient to accommodate a friction disc 34 provided with a facing of felt or the like 35 and a spacing plate 36 which serves also as a ball race for the ball bearings 37. By making the central apertures in the disc 34 15 and the plate 36 of slightly greater diameter than that of the finger 31, the friction disc 34 can, in conjunction with the rounded head of the bolt 26 and the ball bearings 37, partake of a substantial amount of universal action and thus accommodate itself to the surface of any record in the 20 stack regardless of the level of that record.

25 When stacked on the turntable for playing, the records R are threaded on the center pin 5 and the free end of the ejector arm is permitted to rest upon the topmost record of the stack with the arm inclined downwardly toward the records about 3° to the surface of the turntable. In this position, the mass or roller M will roll down the inclined base 23 until it strikes the bumper 29 30 which will absorb the shock thereof, and the weight of the roller M plus most of the weight of the ejector arm will be concentrated upon the records through the friction disc 34 which directly engages the topmost record of the stack 35 and through which sufficient pressure is applied to the stack to prevent slipping of the records relative to each other during reproduction. The head 32 of the finger 31 is so adjusted that, when the friction disc 34 is in engagement with the topmost record of the stack, the head 32 will depress the center pin 5 the thickness of only one record (Figure 1). It will be noted that the diameter of the head 32 is the same as that of the center pin 5 and also the same as the diameter of the center openings of the record. This, of course, is to keep the topmost record properly centered as it rotates, during reproduction, about the head 32, although deriving its 40 rotary motion from the records below it by reason 45 of the pressure applied through the disc 34.

50 At the completion of playing of a record, the tone arm is removed therefrom and the cam plate 19 is actuated in a clockwise direction about the bushing extension 10a through its downwardly extending pin 38 by means of an actuating member 39 which is operated by any suitable mechanism, such as that fully shown and described in the aforesaid co-pending application of Benjamin R. Carson, for example, although 55 the specific mechanism is immaterial to the present invention. Thereupon, the portion A—B of the cam plate 19 engages the pin 17 to move the yokes 12 and 14, and with them the arm 22, horizontally in a clockwise direction whereby the 60 ejector arm removes the topmost record from the stack, since the center pin depressing finger 31 keeps the center pin 5 depressed just below the said record.

65 Fixed to the motor board 1 is a second cam 70 plate 40 having its cam edge 41 so overlapping a portion of the slot 18 that it lies in the path of movement of the pin 17. At about the time the ejector arm 22 has moved the played record to a position where the center of the record is just 75

past the peripheral edge of the next lowermost record, the pin 17 engages the cam edge 41 and, as the pin 17 is forced thereover by the continued clockwise movement of the cam plate 19, the pin 5 17 is raised rather rapidly forcing the yoke 14 upwardly and with it the ejector arm also by engagement of the screw 21 with the base 23. The cam plate 19 is arranged to continue its clockwise movement at this time, and the combined effect of the cam plates 19 and 40 on the ejector arm 22 is to give it a sort of "whipping action", whereby it "whips" the played record off into a played record receptacle (not shown). By this time, an extension 42 on the yoke 12 15 has reached a fixed stop 43 on the motor board 1, thus limiting further movement of the yoke 14 in a clockwise direction. However, the cam plate is arranged to continue its clockwise advance somewhat, as fully disclosed in the aforesaid co-pending application of Benjamin R. Carson, and, as it continues its clockwise advance, the cam portion B-C thereof raises the pin 17 away from the cam edge 41. Thereupon, a spring 44, fixed at one end to a pin 45 on the motor 20 board 1 and at the other end to a pin 46 extending downwardly from the yoke 12, pulls the yoke 12 back slightly in a counter-clockwise direction and forces the pin 17 into the dwell D of the cam plate 19 and against a finger 47 extending 25 from the plate 19.

At this time, the ejector arm has been raised to an intermediate position inclined away from the turntable about 3° to the plane thereof. This angle is sufficient to cause the roller M to roll 30 back along the base 23 from its position in Figure 1 to the solid line position of Figure 3 where the center of gravity thereof is in substantial vertical alignment with the longitudinal axis of the pin 13, the shock absorber 30 now acting to absorb 35 the shock thereof. When the ejector arm is subsequently returned, by means fully described in the above-identified Carson application and, while in its aforesaid intermediate position, to a point such that its center pin depressing finger 40 is in axial alignment with the center pin 5, as determined by the engagement of the extension 42 with an adjustable stop 48 on the motor board, and the ejector arm thereafter is lowered onto the next succeeding record of the stack, the 45 roller M is ineffective to force the ejector arm down and to apply pressure to the stack, and the ejector arm 22 gently engages the new record upon being lowered. As soon, however, as the friction disc 34 has engaged the new record so 50 that the ejector arm is inclined toward the turntable again at least 3° , the roller again moves down into the position shown in Figure 1 against the member 29, whereupon its weight exerts a force on the stack sufficient to maintain the 55 records thereof in desired frictional relation.

When loading records on the turntable, it is, of course, necessary to move the arm 22 out of the way of the turntable and to insure its remaining out of the way so that it will not accidentally fall upon and injure the records. This may be accomplished by raising the ejector arm to the dot-and-dash line position of Figure 3 against a stop 49. In this elevated position, the arm 22 is inclined away from the turntable approximately 60° and the center of gravity of the roller M is then to the left of the pin 13, the roller M being then at the point of least elevation of the arm 22. The roller M then serves to counterbalance the arm 22 since its moment of inertia about the pin 13, in a counterclockwise di-

rection, is greater than the moment of inertia of the arm 22 about the pin 13 in a clockwise direction. Thus, the ejector arm 22 will be held positively in its elevated position without any danger of accidentally falling upon the records 5 on the turntable.

Although I have shown and described a certain specific embodiment of my invention, it will be apparent to those skilled in the art that many modifications thereof and changes therein are 10 possible without departing from the spirit thereof. For example, in place of the mass M, the ejector arm may be provided with a dash-pot arrangement to cushion its fall upon the records. Also, if desired, a suitable latch member may 15 be employed to positively latch the ejector arm in its elevated position when raised thereto. Moreover, where a movable mass is employed, as described herein, the mass may be a sliding instead of a rolling member, and the guides 24 20 may be eliminated, if desired. Other changes will, no doubt, readily suggest themselves to those skilled in the art. My invention, therefore, is not to be restricted except insofar as is necessitated by the prior art and by the spirit of the 25 appended claims.

I claim as my invention:

1. In a phonograph, a record transfer arm adapted to engage a record and mounted for movement toward and away from the record, and 30 means associated with said arm for variably controlling the force with which said arm engages the record.

2. In a phonograph including a record support, a record transfer arm adapted to engage a record 35 on said support, said arm being mounted to one side of said support for movement toward and away from the record, and means movably mounted on said arm for controlling the force with which said arm engages the record, said 40 controlling means being movable in response to movement of said arm toward and away from the record.

3. In an automatic phonograph of the type 45 wherein a plurality of records are stacked upon the turntable for successive reproduction, a record ejector arm adapted to engage and press against the topmost record of the stack whereby to press all the records in the stack against the turntable for rotation therewith as a unit, and 50 means for varying the degree of pressure applied by said arm to the record stack.

4. In an automatic phonograph of the type 55 wherein a plurality of records are stacked upon the turntable for successive reproduction, a record ejector arm adapted to engage and press against the topmost record of the stack, said arm being mounted for movement toward and away from the stack, and means movably mounted on said arm and movable in response to movement 60 thereof for controlling the force with which said arm initially engages the topmost record of the stack and for thereafter controlling the pressure applied by said arm to said stack.

5. The invention set forth in claim 4 characterized in that said controlling means comprises a roller of substantial mass.

6. The invention set forth in claim 4 characterized in that said record ejector arm comprises a hollow structure and characterized further in 70 that said controlling means comprises a roller of substantial mass movable within said hollow structure.

7. In a phonograph, the combination of a record support and a record ejector arm, said arm 75

- being mounted to one side of said support for pivotal movement in a vertical direction toward and away from said support and being adapted, when in its lowered position, to engage a record on said support, and a mass freely movable on said arm in response to movement thereof.
8. In a phonograph, the combination of a record support and a record ejector arm, said arm being mounted to one side of said support for pivotal movement in a vertical direction toward and away from said support and being inclined toward said support when in lowered position, in which position said arm is adapted to engage a record on said support, and a mass freely movable on said arm in response to movement thereof, said mass being adapted to assume a position to cause said arm to exert a relatively great force on the record when said arm is in engagement therewith.
9. In a phonograph, the combination of a record support and a record ejector arm, said arm being mounted to one side of said support for pivotal movement in a vertical direction between a lowered position inclined toward said support and a raised position inclined away from said support, a mass freely movable on said arm in response to movement thereof between said positions, said arm being adapted, in its lowered position, to engage a record on said support, and said mass being adapted to assume a position on said arm when said arm is in said lowered position to cause said arm to exert a relatively great force on the record and being adapted, when said arm is in said raised position, to assume a position such that when said arm is again lowered onto a record on said support said arm will initially engage the record with a relatively small force.
10. In a phonograph, the combination of a record support and a record ejector arm, said arm being mounted on an axis adjacent said support for pivotal movement in a vertical direction between a lowered position inclined toward said support at a relatively small angle and an elevated position inclined away from said support at a relatively great angle and said arm being adapted, when in said lowered position, to engage a record on said support, means for raising said arm to a position intermediate said lowered and elevated positions wherein said arm is inclined away from said support at a relatively small angle, a weighted roller freely movable on said arm, said axis lying intermediate the ends of said arm and extending transversely thereof whereby said roller is adapted, when said arm is raised to its elevated position, to occupy a position wherein its center of gravity is on that side of said axis which will cause said roller to positively maintain said arm in said elevated position, said roller being also adapted to occupy a position wherein its center of gravity is in substantial vertical alignment with said axis when said arm is in said intermediate position whereby said arm is free to engage the record with comparatively small force, and said roller being further adapted to occupy a position on the other side of said axis when said arm is in said lowered position whereby said arm is adapted to exert a relatively great force on the record.
11. The invention set forth in claim 10 characterized in that said arm is so mounted with respect to said support that, in said elevated position, said arm is inclined approximately 60° to said support; in said intermediate position, said arm is inclined substantially 3° to the record on said support; and in said lowered position,
- said arm is inclined not less than 3° to the record on said support.
12. In a phonograph including a record support, a record ejector arm mounted for pivotal movement in a vertical direction relative to said support, said arm being free to move to an elevated position inclined away from said support, and a movably mounted mass on said arm adapted to be positioned to positively maintain said arm in said elevated position when said arm is raised thereto.
13. In a phonograph including a record support, a record ejector arm mounted between its ends and adjacent one of them on an axis to one side of said support for pivotal movement in a vertical direction relative to said support, said arm being free to move to an elevated position inclined away from said support, and a mass freely movable on said arm, said mass being adapted to occupy a position, when said arm is in elevated position, such that its center of gravity lies on that side of said axis on which the point of least elevation of said arm lies.
14. A record transfer arm comprising a hollow, elongated member, a record engaging member on one end thereof, and a mass movable within said member whereby its center of gravity may be changed.
15. A record transfer arm comprising a hollow, elongated member, a record engaging member on one end thereof, and a weighted roller movable within said member whereby its center of gravity may be changed.
16. A record transfer arm comprising a hollow, elongated member, a record engaging member on one end thereof, a mass movable within said member whereby its center of gravity may be changed, and a shock absorbing device adjacent each end of said member adapted to cooperate with said mass to absorb the shock thereof as it comes to rest after a period of movement.
17. A record transfer arm comprising a base member provided with a pair of spaced, upstanding guides, a cover on said base member enclosing said guides and providing a hollow space bounded by said guides, said base member and said cover, a record engaging member on one end of said base member, a weighted roller in said hollow space freely movable between said guides from substantially one end of said arm to the other end thereof, and resilient means adjacent each end of said arm for absorbing the shock of said roller as it comes to rest after a period of movement in either one direction or the other along said arm.
18. In an automatic phonograph of the type wherein a plurality of records are stacked upon the turntable for successive reproduction, a record ejector arm for removing the respective topmost records from the stack, said arm being normally supported in angular relation to the records in the stack, means on said arm for engaging the topmost record of the stack, means including a universal coupling whereby said record engaging means may accommodate itself to the surface of any record in said stack, and means movable along said arm for varying the pressure exerted by said arm on said stack.
19. In a phonograph including a record support, a record transfer arm mounted between its ends for pivotal movement in a vertical direction relative to said support, and a mass freely movable on said arm between a point over said support and a point clear of said support in re-

spouse to movement of said arm about its pivotal axis.

20. In a phonograph including a record support, a record transfer arm mounted on an axis to one side of said support for pivotal movement in a vertical direction relative to said support, and a mass freely movable on said arm between a point over said support and a point adjacent said axis in response to movement of said arm.

10 21. In a phonograph including a record support, a record transfer arm mounted on an axis to one side of said support for pivotal movement in a vertical direction relative to said support, said axis lying intermediate the ends of said arm

and extending transversely thereof, and a mass freely movable on said arm between a point on one side of said axis to a point on the other side thereof in response to movement of said arm.

22. In a phonograph including a record support, a record transfer arm mounted on an axis to one side of said support for pivotal movement in a vertical direction relative to said support, said axis lying intermediate the ends of said arm and extending transversely thereof, and a mass 10 freely movable on said arm between the ends thereof in response to the pivotal movement of said arm.

JOHN H. TEAF.
